H. JUNKERS.
PANEL ROD.
APPLICATION FILED JUNE 28, 1920.

1,424,912.

Patented Aug. 8, 1922.

Inventor:

Hugo Junkers

UNITED STATES PATENT OFFICE.

HUGO JUNKERS, OF DESSAU, GERMANY.

PANEL ROD.

1,424,912.

Specification of Letters Patent. Patented Aug. 8, 1922.

Application filed June 28, 1920. Serial No. 392,589.

(GRANTED UNDER THE PROVISIONS OF THE ACT OF MARCH 3, 1921, 41 STAT. L. 1313.)

To all whom it may concern:

Be it known that I, Hugo Junkers, a citizen of the German Empire, residing at Dessau, Germany, have invented certain 5 new and useful Improvements in Panel Rods (for which I have filed applications in Germany January 30, 1918, Netherlands June 21, 1919, Sweden December 6, 1912, Norway December 31, 1919, Denmark December 19, 10 1919), of which the following is a specification.

This invention relates to panel rods and more especially to sheet metal strips adapted to take up pressure acting in a longitudinal 15 direction by being contracted transversely in such a manner, that longitudinally extending corrugations are produced, which are deepest in the middle and are gradually becoming flatter towards the ends. Preferably the longitudinal edges of the rod are bent at right angles in opposite directions 20 all over the length of the rod.

In the drawings affixed to this specification and forming part thereof the preferred 25 form of a panel rod embodying the principles of my invention is illustrated. In the drawings

Fig. 1 is a perspective view and

Fig. 2 is a cross section taken on the line 30 I—I in Fig. 1.

The rod shown in the drawings is formed of a flat sheet metal strip whose longitudinal edges *a* and *b* are bent at right angles in opposite directions throughout 35 the length of the rod. At the assembling points the edge directed towards the contacting surface is beveled or cut off as shown at *e*, so that a straight contacting face is produced on the strip. The rod is

shown as being attached to tubular frame 40 work rods *f* by means of rivets *g*. The greater part of the rod is contracted transversely in such a manner, that longitudinally extending corrugations (*c* and *d*) are produced. Towards the ends of the rod the corrugations become gradually flatter and terminate in the straight end portions *h*.

I claim:

1. A sheet metal panel rod comprising flat end portions and a middle portion contracted transversely and having a longitudinal corrugation formed therein. 50

2. A sheet metal panel rod comprising flat end portions and a middle portion contracted transversely and having a longitudinal corrugation formed therein, whose walls are highest in the middle of the rod. 55

3. A sheet metal panel rod comprising flat end portions and a middle portion contracted transversely, and having a longitudinal corrugation formed therein, the longitudinal edges of said rod being bent 60 at right angles.

4. A sheet metal panel rod comprising flat end portions and a middle portion contracted transversely and having a longitudinal corrugation formed therein, the longitudinal edges of said rod being bent at right angles in opposite directions. 65

5. A sheet metal panel rod comprising flat end portions and a middle portion contracted transversely and having a longitudinal corrugation formed therein, the longitudinal edges of said rod being bent at right angles and one of said edges being 70 bevelled at both ends. 75

In testimony whereof I affix my signature.
HUGO JUNKERS.
